CLAIM

The ornamental design for an animal watering fountain, as shown and described.

DESCRIPTION

FIG. 1 is a front top left perspective view of an animal watering fountain.

FIG. 2 is a front top right perspective view thereof.

FIG. 3 is a front view thereof.

FIG. 4 is a rear view thereof.

FIG. 5 is a left view thereof.

FIG. 6 is a right view thereof.

FIG. 7 is a top view thereof; and,

FIG. 8 is a bottom view thereof.

The broken lines illustrate portions of the animal watering fountain that form no part of the claimed design.
